FLOW CONTROL OF PULVERANT MATERIAL
Edward J. Ostrowski, Steubenville, Ohio, and Hiram C. Kozak, Lackawanna, and Harold A. Putnam, Buffalo, N.Y., assignors to National Steel Corporation, a corporation of Delaware

Filed May 22, 1962, Ser. No. 196,767
4 Claims. (Cl. 302—53)

This invention relates generally to controlling flow of finely divided solids and, more particularly, to improved methods and apparatus for uniformly feeding pulverant material into a flowing gas stream at a constant rate.

In the past, schemes for feeding finely divided solids have generally relied on gravity and/or mechanical vibration, magnetic properties of the material or mechanical feed rotors. Precise control of pulverant material flow has however been lacking in the art. The pneumatically controlled system disclosed herein provides precise control of pulverant material flow while meeting such requirements as continuous operability, uniform and constant flow rate, and feed into a variable pressure system.

A difficult problem in pulverant material distribution is obtaining and maintaining fluid flow properties in the finely divided material being distributed. This problem is compounded in a pressure controlled system since steps to maintain fluid flow properties in the pulverant material are likely to upset the pneumatic control. In overcoming this and other problems, the teachings of the invention make possible a pneumatic system for pulverant material distribution which functions with accuracy comparable to that available in gaseous or liquid flow control systems. In so doing, pulverant materials may be used in applications where heretofore, their use has been practically nonexistent. As an example of the latter, liquid and gaseous fuels have been used increasingly in the steel industry to supplant coke in blast furnaces. Pulverized solid fuels have not been able to meet operational requirements and have not been used commercially. With the teachings of the present invention, however, flow control pulverant material is available permitting pulverized solid fuels to be used equally as well as liquid or gaseous fuels in supplanting blast furnace coke. As a result, the more costly coke can be replaced by a less costly fuel coal.

Flow control requirements in iron producing operations are as arduous as can be found in most commercial operations, therefore the invention will be described in this environment. In the blast furnace art, a portion of the blast furnace coke which is normally introduced at the top of the furnace can be replaced with an auxiliary fuel introduced at the bottom of the furnace, generally, with the blast through the blast furnace tuyeres. Part of the problem in adding auxiliary fuels to blast furnaces stems from the physical characteristic of commercial blast furnaces. Coke, for example, introduced at the top of the blast furnace may take 8 to 10 hours, or longer, to reach the combustion zone where most of its heating properties are utilized. When supplanting a portion of this coke with auxiliary fuels introduced at the bottom of the furnace, these auxiliary fuels must be introduced uniformly over extended periods of time to provide the quantitative precision normally required in charging blast furnace materials. Further, these fuels must generally be fed into a blast which is subject to variations in pressure and is often subject to complete interruption. A primary object of the invention is to make possible introduction of pulverized solids into a blast furnace system for entrainment in the blast (1) on a continuously available basis, (2) over unlimited periods of time and (3) with uniformity independent of variations in blast pressure.

In describing a specific embodiment of the invention

2

reference will be had to the accompanying drawings wherein like numbers are used to designate like structures. In these drawings,

FIGURE 1 is a schematic diagram apparatus for introducing pulverant material into a blast furnace system, and

FIGURE 2 is a detailed schematic diagram of portions of FIGURE 1 including control apparatus for introducing a pulverant material into a system.

Referring to FIGURE 1, pulverant material from source 9 is supplied via conveyance means 10 and 11 to storage tanks 14 and 15, respectively. Conduit 16 connects storage tank 14 in series with injector tank 18; storage tank 15 is similarly connected through conduit 17 with injector tank 19. Pulverant material is delivered from injector tanks 18 and 19 through identical distributor conduits 22. Carrier gas pipes 23 are in receiving relationship to distributor conduits 22 and deliver the pulverant material to the tuyeres of blast furnace 24. Hot blast is delivered to the blast furnace 25 via bustle pipe 25 and hot blast main 26.

Pneumatic pressure for the pulverant material distribution system is supplied from gas source 27. Conduits 28 and 29 supply carrier gas to pipes 23. Conduits 30 and 31 supply gas from gas source 27 to pulverant flow control means 32 and 33, respectively.

The pneumatic pressure supplied through pulverant material flow control means 32 and 33 to the injector tanks 18 and 19, respectively, controls the amount of pulverant material delivered to the blast furnace system. More specifically, the amount of pulverant material distributed is dependent upon the difference in pneumatic pressure between the higher-pressure injector tanks and the lower-pressure delivery point in the blast furnace system. However, pressure differential alone is not sufficient to maintain flow of pulverant material. Without the additional structures and control features provided, to be described, pulverant material would merely pack about the area of distributors 22 and it would be impossible to obtain flow when desired.

In FIGURE 2, a portion of the distribution system of FIGURE 1 is shown with such additional structure and control features in more detail. The injection system is rendered continuously operable by connection of the storage tanks and injector tanks in series. With this arrangement, an injector tank may be recharged from a storage tank with both tanks on the line and a storage injector tank may be isolated from the injector tank for recharging while the series connected injector tank remains on the line. Valve 36 opens or closes conduit 16. Valve 38 closes storage tank 14 so that this tank may be pressurized when on the line. Flow of pulverant material from source 9 to storage tank 14 may be by any suitable means while flow of pulverant material from the storage tank 14 and from the injector tank 18 is pneumatically controlled.

For purposes which will be discussed later in describing operation of the system: a pressure equalizer line 40 is connected between tanks 14 and 18; valve 42 is included in this line; vent line 46 is connected to injector tank 18 and includes vent valve 48; vent line 50 is connected to storage tank 14 and includes valve 52; vent lines 46 and 50 are interconnected by crossover line 54 which includes a valve 56, and pressurizing conduit 60 is connected to injector tank 18 and includes flow control valve 62.

A pressure differential between injector tank 18 and the blast furnace system is in itself not sufficient to cause uniform flow because of packing of pulverant material at the bottom of injector tank 18. To offset this difficulty a fluidizing cone 64 is provided at each distributor tube 22. Fluidizing gas continuously discharges tangentially within cones 64 to maintain the pulverant material in a fluid or semi-fluid state and responsive to pressure con-

Vent valves 48 and 52 normally vent to the atmosphere. However, after refilling of storage tank 14, this tank may be brought up to a pressure approximating that of injector tank 18 by venting injector tank 18 into storage tank 14. In this operation, vent valves 48 and 52 and auxiliary pneumatic pressure valve 70 are closed. Crossover valve 56 is opened and injector tank 18 is vented into storage tank 14. When the pressure in storage tank 14 equals that in injector tank 18, valve 56 may be closed and vent valve 46 opened to vent injector tank 18 to the atmosphere or venting may be controlled through valve 52, and storage tank 14 maintained at the same pressure as injector tank 18 via crossover 54. These operations can be made automatic by solenoid operated valves or pressure sensitive valves.

With the apparatus thus far described, the injector tank 18 pressure rises or falls with the hot blast main 26 pressure. In the event the hot blast main pressure falls radially, for example during casting of the blast furnace, it is not desirable to have the injector tank pressure follow down the full scale because of a time lag which can be incurred when bringing the injector tank 18 pressure up to the required level after hot blast main pressure is restored. To overcome this problem, provision is made to automatically stop venting when the hot blast main pressure falls below a selected point. To execute this control feature, the blast main pressure measurement is delivered over signal line 98 to pressure switch 100 in circuit 102. Closing of switch 100 delivers power to relay 104 which opens switch 106 terminating delivery of power to vent valve interlock 94. This stops venting of the injection system until the pressure in the hot blast main 26 returns to the selected level; at this point, normal venting control takes over.

In utilizing this invention for injecting pulverized fuel into a blast furnace system the percentage of blast furnace coke to be replaced is determined and the flow rate of pulverized fuel required is calculated. Among other things, the type of pulverized fuel affects this calculation; typical fuels include pulverized coal, coke, char, or other carbonaceous materials. The gas employed may also affect this calculation; normally air would be employed, but enrichment with oxygen or gaseous fuels is also within the scope of the invention. It may also be desirable to add other pulverized materials such as lime, ores, blast furnace fines, etc., and provision can be made for adding these materials in addition to or in place of the pulverized fuel. Considering addition of pulverized fuel only, after determining the desired percentage of total fuel requirement to be injected as auxiliary fuel (typically up to about 30%), the required flow rate, in weight units per unit of time is calculated. The required pressure differential to maintain this flow rate is predetermined and introduced to differential pressure control 75 as previously pointed out. Injector tank 18 is brought up to original pressure via flow control valve 62 and flow of pulverized fuel is initiated. Flow is then maintained under the controls described. Injector tank 18 is periodically recharged from storage tank 14 utilizing the cycle of operation described earlier. The sequential operation of pressurizing, venting, and recharging valves can be timed and operated automatically by sequence timer 108 within the teachings of the invention. Operation of a sequence timer is well known in the art and, with the cyclical operation described herein, no further explanation for automatic operation should be required by one skilled in the art.

The methods and apparatus described herein may be utilized for pressured-controlled introduction of finely divided solids into a pressurized or non-pressurized system and can maintain uniform flow at a constant flow rate of the material on a continuously operable basis.

We claim:

1. Apparatus for pneumatically providing a uniform

and constant flow rate of pulverant material into a variable pressure blast furnace system comprising
injector tank means for holding pulverant material under pressure,
5 pneumatic pressurizing means for maintaining the injector tank means under pressure including pneumatic flow control valve means,
distributor means for delivering pulverant material from the injector tank means including fluidizing means for the pulverant material contiguous with the distributor means,
conduit means for delivering fluidizing gas to the fluidizing means to continuously maintain pulverant material in a fluid state,
venting means for the injector tank means including vent control valve means,
control means for maintaining a substantially constant pressure differential between the injector tank means and the blast furnace system while maintaining pulverant material in a fluidized state, the control means including,
means for measuring the pressure differential between the injector tank means and the blast furnace system pressures,
means for comparing the measured pressure differential to a predetermined desired pressure differential and generating a signal in response thereto to control the flow control valve means and the vent control valve means to maintain a constant pressure differential between the injector tank means and the blast furnace system.

2. Apparatus for pneumatically providing a uniform and constant flow rate of pulverant material into a variable pressure blast furnace system on a continuously operable basis comprising

storage tank means for storing pulverant material under pressure,

injector tank means for holding pulverant material under pressure,

conduit means interconnecting the storage tank means and injector tank means for recharging the injector tank means from the storage tank means while maintaining the storage and injector tank means under pressure,

pneumatic pressurizing means for maintaining the injector tank means under pressure including pneumatic flow control means for raising pneumatic pressure within the injector tank means to selective levels,

distributor means for delivering pulverant material from the injector tank means including fluidizing means contiguous with the distributor means,
means for delivering fluidizing gas to the fluidizing means to continuously maintain pulverant material about to be delivered from the injector tank means in a fluid state,

venting means for the injector tank means and the storage tank means including vent control means, pressure equalizing means connected between the injector tank means and the storage tank means, and control means for maintaining a substantially constant pressure differential between the injector tank means and the blast furnace system including
means for measuring the pressure differential between the injector tank means and the blast furnace system,

means for comparing the measured pressure differential to a predetermined pressure differential and generating a signal for controlling the flow control valve means and the vent control valve means, and
means for terminating venting of the injector tank means when pressure of the blast furnace system falls below a pre-selected level.

3. Method for injecting pulverant solid fuel into an iron producing blast furnace system at a uniform rate in which pulverized solid fuel held in container means

under pressure is continuously available to be delivered to the blast furnace system for entrainment in the hot blast main comprising the steps of

- supplying gas to the container means for the pulverized solid fuel to maintain the container means under pressure, 5
- continuously supplying fluidized gas to the container means for maintaining pulverized solid fuel about to be delivered from the container means in a fluid state, 10
- measuring the pneumatic pressure of the container means, 15
- measuring the pneumatic pressure at a pre-selected reference point in the hot blast main, 20
- measuring the pneumatic pressure differential between the pneumatic pressure of the container means and the hot blast system, 25
- and controlling supply of pneumatic pressure to the container means and venting of the container means to maintain a predetermined pneumatic pressure differential.

4. Apparatus for pneumatically providing a uniform and constant flow rate of pulverant material into a pressurized gas stream on a continuously operable basis comprising
- a storage tank means for storing pulverant material under pressure, 30
  - injector tank means for holding pulverant material under pressure, 35
  - conduit means interconnecting the storage tank means and injector tank means for recharging the injector tank means from the storage tank means while maintaining the storage and injector tank means under pressure, 40
  - pneumatic pressurizing means for maintaining the in- 45

jector tank means under pressure including pneumatic flow control means for raising pneumatic pressure within the injector tank means to selective levels,

distributor means for delivering pulverant material from the injector tank means including fluidizing means contiguous with the distributor means, means for delivering fluidizing gas to the fluidizing means to continuously maintain pulverant material about to be delivered from the injector tank means in a fluid state,

venting means for the injector tank means and the storage tank means including vent control means, pressure equalizing means connected between the injector tank means and the storage tank means, and control means for maintaining a substantially constant pressure differential between the injector tank means and the pressurized gas stream including means for measuring the pressure differential between the injector tank means and the pressurized gas stream,

means for comparing the measured pressure differential to a predetermined pressure differential and generating a signal for controlling the flow control valve means and the vent control valve means, and means for terminating venting of the injector tank means when pressure of the pressurized gas stream falls below a preselected level.
